UNITED STATES PATENT OFFICE.

RALEIGH H. STALEY, OF SPRINGFIELD, ILLINOIS, ASSIGNOR TO THE BAKER MANUFACTURING COMPANY, OF SPRINGFIELD, ILLINOIS, A CORPORATION OF ILLINOIS.

FRAME CONSTRUCTION.

Application filed February 23, 1926. Serial No. 90,047.

My invention relates to new and useful improvements in frame constructions and more particularly to a vehicle frame construction for use in connection with road scrapers or graders or dump wagons and the like, the principal object of the invention residing in the provision of a frame embodying considerable strength whereby repairs and replacements are reduced to a minimum.

A further object of the invention resides in the construction of the frame in such a manner that in haulage the pull is substantially on a line with the front axle this allowing for ready attachment to the ordinary form or average tractor, the tongue which is attached to the frame being in a position to be readily attached to the draw bar of the tractor.

With the above and other objects in view, which will appear as the description proceeds, my invention consists in the novel details of construction and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a perspective.

Fig. 2 is a top plan.

Fig. 3 is a side elevation, and

Fig. 4 is a rear end view.

In carrying out my invention the main portion of the frame is formed of two steel channels on each side, heavily braced and gusseted, making a strong truss like construction. The lower side channels are shown at 1 and extend on a horizontal plane as shown more particularly in Fig. 3 with their forward ends turned inwardly to meet at a point shown at 2. The rear ends of the channels 1 are connected together by means of the channel iron shown at 3, this channel iron 3 being secured to the side channels by means of rivets, bolts, or other suitable fastenings.

Secured to the upper surface of the channel 3, at each end thereof, is a wear plate 4 and depending from the channel 3 are the substantially Z-shaped brackets 5 which support the wooden step shown at 6. Extending rearwardly from

the channel 3 are the vertically spaced plates 7 having adjacent their outer ends the aligned openings 8 by means of which another vehicle may be secured in tandem. The plates 7 are secured to the channel 3 by means of rivets, bolts, or other suitable fasteners shown at 9.

The upper side channels are shown at 10. These channels 10 are spaced vertically from the channels 1 but extend parallel therewith, the forward ends being curved inwardly as shown at 11 to meet at the point 12. The rear ends of the channels 10 are downwardly inclined as shown at 13 and at their outer ends contact with the upper surfaces of the channels 1. The channels 10 are of less length than the channels 1 as quite clearly shown in Figs. 1 and 3 of the drawings. The rear ends of the channels 10 are connected to the channels 1 by means of the plates 14, the plates being secured to the channels by means of rivets, bolts, or other suitable fastenings shown at 15. These plates are of such a height as to depend a short distance below the channels 1. The channels 1 and 10, at the points where their forward ends are directed inwardly are connected together by means of the plates 16, the plates being secured to the channels by means of the rivets, bolts or other suitable fastenings shown at 17. Plates 18 connect the channels 1 and 10, intermediate the plates 14 and 17, and are secured to the channels by means of the rivets, bolts, or other suitable fastenings shown at 19. A tie rod 20 connects the inwardly directed portions 11 of the channels 10 as more clearly illustrated in Figs. 1 and 2 of the drawings. Vertically spaced cross channels 21 and 22 connect the channels 10 and 1 respectively at the points where the channels are directed inwardly and these cross channels are connected at their ends by means of the vertically extending plates or strips 23 which are secured to the channels by means of rivets, bolts, or other suitable fastenings.

A substantially V-shaped plate 24 is secured in the pointed end of the frame and depends below the lower channels 1 as shown more particularly in Figs. 1 and 3 of the drawings. This plate is secured to the channels 1 and 10 by means of the rivets, bolts or other suitable fasteners 25 and secured to the inner surface of the plate 24 is 110

a substantially V-shaped plate 26 this plate 26 being secured to the plate 24 by means of the rivets, bolts or other suitable fastenings shown at 27. Secured to the plate 26, adjacent the lower end thereof, is a bearing plate 28 which, with the plate 26, forms an opening for the vertically extending pin or spindle 29 of the front axle bolster shown generally at 30. This front axle bolster forms the subject matter of a separate application and further detail description thereof is not thought necessary at the present time. The wheels 31 are carried by the front axle. The rear axle shown at 32 is secured to the lower side channels 1 by means of the brace blocks 33 one end of the block being secured to the channel 1 by means of the bolts 34 or other suitable fastener and the opposite end being connected to the axle by means of the bolt 35 or other suitable fastening. The rear supporting wheels are shown at 36.

From the above detail description it will be seen that I have provided a vehicle frame construction of great strength and in which the pull of the tractor or other conveying mechanism is in alignment with the front axle. The body portion or main portion of the frame is formed of the vertically spaced parallel channels which are connected by suitable brace plates as well as transversely extending tie rods and channel strips. The channel which connects the rear ends of the lower channels 1 acts as a support for the plates to which another vehicle may be connected as well as a support for the brackets which carry the step. The plates 14, 16 and 18, not only act for connecting the upper and lower channels but may be used as wear plates or plates against which the mechanism carried by the frame may contact. When the plates become worn they may be very easily replaced. The forward ends of the channels 1 and 10 are directed inwardly to form a point at the forward end of the frame to which the plates described may be connected for connection of the front axle bolster. The frame will resist heavy strain and therefore is particularly adapted for use in connection with mechanism adapted to be conveyed from place to place by a tractor or the like and while the frame illustrated and described is more particularly adapted for use with road scrapers or graders it may be as readily used for dump wagons or the like.

Having fully described my invention what I claim as new and desire to secure by Letters Patent is:

1. A frame of the character described including transversely spaced lower side members having their forward ends bent inwardly to contact at the longitudinal center of the frame, upper side members extending parallel with the lower members with

their forward ends bent inwardly to contact at the longitudinal center of the frame, the rear portions of the upper members being inclined downwardly so that the extreme ends of the upper members contact with the lower members, the upper and lower members being vertically spaced except at the extreme rear ends of the upper members, and means connecting the upper and lower members. 75

2. A frame of the character described including transversely spaced lower side members having their forward ends bent inwardly to contact at the longitudinal center of the frame, upper side members extending parallel with the lower members with their forward ends bent inwardly to contact at the longitudinal center of the frame, the rear portions of the upper members being inclined downwardly so that the extreme ends of the upper members contact with the lower members at a point removed from the extreme rear ends of the lower members, the upper and lower members being vertically spaced except at the extreme lower ends of the upper members, and means connecting the upper and lower members. 80 85

3. A frame of the character described including transversely spaced lower side members having their forward ends bent inwardly to contact, upper side members extending parallel with the lower members with their forward ends bent inwardly to contact, the rear portions of the upper members being inclined downwardly so that the extreme ends of the upper members contact with the lower members, the upper and lower members being vertically spaced except at the extreme rear ends of the upper members, and means for connecting together the upper and lower side members at the point where the forward ends of the upper side members and the forward ends of the lower side members contact. 90 95 100 105

4. A frame of the character described including transversely spaced lower side members having their forward ends bent inwardly to contact, upper side members extending parallel with the lower members with their forward ends bent inwardly to contact, the rear portions of the upper members being inclined downwardly so that the extreme ends of the upper members contact with the lower members, the upper and lower members being vertically spaced except at the extreme rear ends of the upper members, and socket forming members connecting together the upper and lower side members at the point where the forward ends of the upper side members and the forward ends of the lower side members contact. 110 115 120

5. A frame of the character described including transversely spaced lower side members having their forward ends bent inwardly to contact, upper side members ex- 125 130

tending parallel with the lower members with their forward ends bent inwardly to contact, the rear portions of the upper members being inclined downwardly so that the 5 extreme ends of the upper members contact with the lower members, the upper and lower members being vertically spaced except at the extreme rear ends of the upper members, and wear plates connecting the upper 10 and lower members.

6. A frame of the character described including transversely spaced lower side members having their forward ends bent inwardly to contact, upper side members ex-

tending parallel with the lower members 15 with their forward ends bent inwardly to contact, the rear portions of the upper members being inclined downwardly so that the extreme ends of the upper members contact with the lower members, the upper and 20 lower members being vertically spaced except at the extreme rear ends of the upper members, and wear plates connecting the upper and lower members at longitudinally spaced points. 25

In testimony whereof I hereunto affix my signature.

RALEIGH H. STALEY.
